SPRAY TYPE OIL BURNER WITH AIR
DIRECTING MEANS

Charles Demuth, Mineola, N. Y.

Application July 13, 1946, Serial No. 683,482

6 Claims. (Cl. 158—76)

1

This invention relates to burners for liquid fuel, such as oil burners, and the invention is intended more especially for burners operating with relatively low pressure air.

Burners of the type contemplated by this invention are intended primarily for use with heating units for domestic or the like use where the combustion chamber or fire box is relatively short and where it is desired to have a loose large flame distributed as evenly as possible over the entire space, and of course as complete combustion as possible is desired for fuel economy. These desirable characteristics require a large amount of air; and in attempts heretofore made to supply extra air two undesirable results have been prominent. First too long a tongue-like close or compact flame, with a resultant roar and a tendency to blow out the flame; and second a flame whose propagation is completed immediately adjacent the burner nozzle and hence not in the desired position substantially centrally of the fire box or combustion chamber.

An object of this invention is to provide an improved burner adapted to supply sufficient air for complete combustion without tending to blow out the flame and producing a relatively large, open, quiet or "lazy" flame propagated at a distance in front of the burner nozzle.

Another object of the invention is to provide a burner capable of facile adjustment and control of the air supply, liquid fuel supply and ignition electrodes.

Other and further objects and advantages of the invention will be apparent from the following description considered in connection with the accompanying drawings, showing a present preferred form of the invention, in which:

Fig. 1 is a side elevational view looking from the fuel pump side;

Fig. 2 is a plan view of the burner shown in Fig. 1, with the top cover removed so as to show certain parts disposed within the casing; and

Fig. 3 is a somewhat enlarged cross-sectional view of the nozzle end of the burner shown in Figs. 1 and 2, taken on a horizontal plane passing through the central axis of the nozzle as shown in Fig. 1.

Referring more particularly to Figs. 1 and 2; a casing 1, preferably made of sheet metal and of rectangular cross section in plan view, provides opposite side walls on which are respectively mounted an electrical motor 2 and an oil or other suitable liquid fuel pump 3 driven by the motor 2, such as by the motor shaft 4. A suitable blower rotor, such as a squirrel cage rotor 5 is con-

2

veniently mounted on the shaft 4. The housing is preferably provided with a suitably shaped partition such as 6 providing a bottom wall for the rotor chamber and preferably spaced from the bottom of the housing to provide a compartment for accommodating a control switch or other suitable control mechanism of the character well known; and a removable rear door 7 provides access to this compartment. The housing 1 is also provided with a removable top panel or door 8 comprising the entire top and part of the back wall of the housing and held in closed position by suitable fasteners such as 9. The top, four side walls and partition 6 provide the blower chamber for the rotor 5. The side walls of the housing are preferably provided with outwardly extending flanges such as 10 providing feet for securing the housing in position.

A cylindrical tubular member 11 is rigidly secured at its inner end to the front wall of housing 1 near its top, as by welding, and its interior is in communication with the blower chamber through an opening provided in the front wall. A slidably adjustable panel 12 is disposed over the blower opening 12a (Fig. 1) in the side wall back of the pump 3, around the shaft 4, to thereby provide for regulating or adjusting the supply of air to the burner nozzle.

The air tube 11 (Fig. 3) is provided with a forward abruptly outwardly flaring annular flange or lip 13. A second cylindrical tubular member 14, of substantially smaller diameter than the tube 11, is disposed concentrically within the tube 11 and rigidly fixed in place as by a plurality of circumferentially spaced radially extending struts such as 15. The front end of the inner air tube 14 is provided with a forward abruptly outwardly flaring annular flange or lip 16 preferably terminating at its forward end beyond the lip 13 and cooperatively disposed therewith to provide an annular outwardly flaring orifice for secondary air. The inner tube 14 is also provided with a forward abruptly inwardly flaring annular flange or lip 17 preferably terminating at its forward end beyond the lip 13 and providing a restricted air orifice for primary air. The rear end of the inner tube 14 is turned inwardly to provide a frusto-conical portion 18 spaced axially forwardly of the housing 1. A secondary air damper ring 19 is slidably disposed within the outer tube 11 and is adjustably secured in axial position by screws such as 20 passing through axially extending slots 21 in tube 11. The ring 19 is tapered to provide oppositely disposed frusto-conical sides the for-

ward edge of which cooperates with the end 18 of tube 14 to provide a variable area throat when moved from the solid line to the dotted line position.

A liquid fuel pipe 22 extends along the axis of the tubes 11 and 14 and at its forward end is provided with a nozzle tip 23 having an atomizing orifice which is disposed adjacent and preferably somewhat forwardly of the primary air orifice provided by the forward edge of the lip 17. The rear end of pipe 22 passes over the top of the rotor 5 (Figs. 2 and 1), spaced upwardly therefrom, and thence laterally outwardly through a slot 24 formed in the casing wall and extending from its rear edge and terminating in a portion parallel with the burner nozzle axis and on the same horizontal level. The end of pipe 22 which is disposed outside said side wall is provided with an L pipe fitting 25 having a hex portion 26 disposed against the outside of said walls, straddling said slot, and a cooperating lock nut 27 is threadingly engaged on said pipe and disposed adjacent the inside of said wall. When in operating position the pipe is rigidly locked to and supported from the side wall by the nuts 26-27. This arrangement provides a facile means of adjusting the pipe and nozzle 23 in an axial direction; and also provides for removing the pipe and nozzle for cleaning or repair by disconnecting the compression coupling 28 (Fig. 1) to detach the flexible oil supply line 29. The pipe 22 is preferably supported intermediate its rear and front end by a suitable bracket such as 30 which is slidingly engaged within the tube 11 and is arranged to permit withdrawal of the pipe as aforesaid and which also serves as a mount for electrodes 31 whose forward firing points 32 are operatively disposed adjacent the nozzle 23.

Operation

With the burner in operation, oil is supplied through the nozzle 23 and primary air through the air nozzle 17 to produce a primary combustible mixture fired by the electrode points 32. This produces a primary flame somewhat of the form diagrammatically illustrated in Fig. 1 and designated 33. By adjusting the intake air damper 12 the primary flame may be adjusted to the desired extent which takes the usual form illustrated. Secondary air is supplied from the outer tube 11 and passes between the damper ring 19 and inner end 18 of the inner tube 14, and thence axially and divergently outwardly through the secondary air nozzle provided between the flanges 13-16 to provide an annular frusto-conical secondary air stream whose longitudinal sectional form is approximately illustrated diagrammatically in Fig. 1 and designated 34. This secondary air stream 34 surrounds or envelopes the primary flame 33 and is spaced outwardly therefrom for a substantial distance axially in front of the burner tip. As viewed in operation it is readily seen that the primary flame continues its normal form for some distance in front of the burner tip, and thereafter the final flame propagation takes place by the gradual supply to the primary flame of secondary air from the stream 34 to produce a large loose or lazy flame and resultant substantially complete combustion. The distance in front of the tip, where the final complete combustion takes place, and the regulation of the volume of air required for complete combustion, may be regulated by axially adjusting the ring damper 19. I have found that in the open position of ring 19 the area of the sec-

ondary air channel should be large enough to supply about 25% of the total air supply.

Having thus described my invention with particularity with reference to a preferred embodiment thereof, and having referred to certain modifications, it will be obvious to those skilled in the art, after understanding my invention, that other changes and modifications may be made therein without departing from the spirit and scope of the invention, and I aim in the appended claims to cover such changes and modifications as are within the scope of the invention.

What I claim is:

1. In a liquid fuel burner, the combination of an inner tube having an inwardly tapered orifice at its forward extremity for supplying primary air, a concentrically disposed outer tube providing jointly with said inner tube an annular outwardly flaring orifice outlet mouth spaced outwardly from and surrounding said first orifice in spaced relation thereto for supplying secondary air in a diverging axial direction, and a liquid fuel tube within said inner tube provided with a nozzle whose orifice is disposed centrally of and adjacent to said primary air orifice, whereby upon combustion of said atomized liquid and primary air an axially directed primary flame is produced within an enveloping diverging secondary air stream to thereby produce complete combustion in a zone spaced forwardly of said primary air nozzle and provide a resultant relatively large flame.

2. In a liquid fuel burner, the combination of an inner tube having a restricted orifice at its forward extremity for supplying a primary air stream, a concentrically disposed outer tube providing jointly with said inner tube an annular outwardly flaring orifice spaced outwardly from said first orifice for supplying secondary air in a diverging axial direction, and a liquid fuel nozzle disposed centrally within said inner tube and terminating adjacent to said primary air orifice, whereby when fuel is emitted into the centrally disposed primary air stream the resultant mixture is ignited and a first relatively dense axially directed primary flame is produced within and enveloped by the wider diverging secondary air stream and thereafter complete combustion takes place in a zone spaced forwardly of said primary air nozzle to provide a relatively large loose flame.

3. In a liquid fuel burner, the combination of an outer air tube provided with an outwardly flaring forward lip, an inner air tube coaxially disposed within said outer air tube and provided with an inwardly directed peripheral forward lip providing a restricted orifice and with an outwardly flaring forward lip cooperatively disposed with respect to said outwardly flaring forward lip provided by said outer air tube providing therewith an outwardly flaring annular orifice surrounding and spaced outwardly from said inner orifice, and a liquid fuel tube extending in an axial direction within said inner tube and terminating at its forward end in a liquid nozzle whose orifice is disposed substantially coaxially within said inner air tube adjacent said restricted orifice.

4. In a liquid fuel burner, the combination of an outer air tube provided with an outwardly flaring forward lip, an inner air tube coaxially disposed within said outer air tube and provided with an inwardly directed peripheral forward lip providing a restricted orifice and with an outwardly flaring forward lip and cooperatively disposed with respect to said outwardly flaring for-

ward lip provided by said outer air tube providing therewith an outwardly flaring annular orifice surrounding and spaced outwardly from said inner orifice, said inner tube being substantially shorter than said outer tube and having an open rear end in communication with said outer tube whereby said outer tube rearwardly of said inner tube provides a common conduit for said inner and outer orifices, and a liquid fuel tube extending in an axial direction within said inner tube and terminating at its forward end in a liquid nozzle whose orifice is disposed substantially coaxially within said inner air tube rearwardly of said restricted orifice.

5. In a liquid fuel burner, the combination of 15 a cylindrical outer air tube provided with an outwardly flaring forward lip, a cylindrical inner air tube coaxially disposed within said outer air tube and whose forward end is bifurcated so as to present respectively inwardly and outwardly diverging peripheral flanges, said inwardly extending flange providing a restricted orifice and said outwardly extending flange being cooperatively disposed with respect to said outwardly flaring forward lip provided by said outer air tube providing therewith an outwardly flaring annular orifice surrounding and spaced outwardly from 25 said inner orifice, said inner tube being substantially shorter than said outer tube and having an open rear end in communication with said outer tube whereby said outer tube rearwardly of said inner tube provides a common conduit for said inner and outer orifices, and a liquid fuel tube extending substantially axially within said inner tube and terminating at its forward end in a liquid nozzle having an orifice spaced axially from 30 said restricted air orifice.

6. In a liquid fuel burner, the combination of 40 a first air nozzle, a second air nozzle concentrically disposed surrounding said first air nozzle in

spaced relation thereto, the outer extremities of said first and second air nozzles jointly providing an annular outwardly flaring orifice for producing an outwardly directed divergent annular air stream, said first air nozzle also providing an inwardly tapered restricted orifice of a smaller diameter than and spaced inwardly from said outwardly flaring orifice, and a liquid fuel nozzle disposed centrally of said first air nozzle, whereby 10 said liquid nozzle and first air nozzle produce a relatively long flame of the combustion mixture supplied within an enveloping air stream supplied by said annular outwardly flaring orifice.
